RESISTANCE COUPLED AMPLIFIER

Walter van B. Roberts, Princeton, N. J., assignor
to Radio Corporation of America, a corpora-
tion of Delaware

Application March 29, 1929. Serial No. 350,949

6 Claims. (Cl. 179—171)

My present invention relates to couplings for amplifier stages, and, more particularly, to a method of, and means for, resistively coupling stages of radio frequency amplification.

5 High frequency resistance-repeating amplifiers are not basically different from the well-known form of low-frequency amplifiers of the same type diagrammatically shown in Figure 1 of the drawing. However, it must be observed that the resistance-repeating amplifier suffers from the fact that at radio frequencies the condensive reactance of the grid-filament circuit becomes so low as to practically short-circuit the repeating resistance, and consequently reduce the amplifying action.

10 Thus, a resistance-repeating amplifier which operates very successfully at audio frequency may fail to amplify at all at radio frequency, not because of any fault of the amplifier, but because of the short-circuiting action of the capacity between the grid and filament of each tube.

15 Now, I have discovered a method of eliminating the detrimental effects of the tube inter-electrode capacities shunted across the repeating resistance which consists in replacing the repeating resistance by a filter system, the tube inter-electrode capacities being employed as a capacity across the filter input terminals, the resulting combination having an impedance which functions as a pure and fairly constant resistance over a predetermined range of frequencies.

20 Accordingly, it is one of the main objects of the present invention to provide a resistance-coupled amplifier including a filter member between each pair of amplifier tubes, the input terminals of each member being connected to a capacity comprising the tube inter-electrode capacities of the aforesaid tubes whereby the filter member functions as a pure resistance over a predetermined range of frequencies.

25 Another important object of the invention is to provide a resistance-coupled amplifier for radio frequency amplification which includes a filter member between each pair of amplifier tubes, each filter having a capacity, comprising the plate-filament capacity of the tube preceding it and the grid-filament capacity of the tube following it, across its input terminals, each filter member thereby functioning as a pure and fairly constant resistance over a predetermined range of frequencies.

30 The novel features which I believe to be characteristic of my invention are set forth in particularity in the appended claims, the invention itself, however, as to both its organization and method of operation will best be understood by

reference to the following description taken in connection with the drawing in which I have indicated diagrammatically several circuit organizations whereby my invention may be carried into effect.

35 In the drawing,

Figure 1 shows diagrammatically a conventional type of resistance-coupled amplifier circuit,

Figure 2 shows diagrammatically the amplifier circuit of Figure 1, with my invention applied thereto,

Figure 3 is a circuit diagram of a modified form of the coupling for the amplifier shown in Figure 2,

Figure 4 is a detail of the circuit shown in Figure 3 including a simplified form of the coupling shown in the latter figure,

Figure 5 is a detail of an amplifier circuit including a coupling member comprising a band pass filter,

Figure 6 shows diagrammatically the amplifier circuit shown in Figure 1, with another modified form of coupling applied thereto.

40 Referring to the accompanying drawing in which like characters of reference indicate the same parts in the different figures, in Figure 1 there is shown a type of resistance-coupled amplifier, well known to those skilled in the art, which is particularly adapted for audio-frequency amplification, and including two stages of amplification comprising tubes 1, 2, of the screen-grid type, it being understood that any other type of electron discharge tube may be employed, the screen element of the tubes being positively biased by sources "S".

45 The antenna circuit A is grounded at G and tuned by a selector, the input circuit of tube 1 being coupled to the latter. The output circuit of tube 1 is coupled to the input circuit of tube 2 by a resistance R_1 connected at one end to the plate of tube 1, and at the other end to the positive terminal of a source "B". A grid condenser C_2 is inserted in the grid circuit of the tube 2, a grid leak r_2 being connected between the grid of tube 2 and the filament of the latter. The output circuit of the tube 2 is coupled to any well known type of utilization means, such as phones, loud speaker, etc.

50 Experience has shown that a simple resistance coupling, such as shown in Figure 1, is useless at radio frequencies due to the short-circuiting effects of tube capacities effectively in shunt to the repeating resistance, as R_1 , such tube capacities being designated as the capacity C_1 and shown in Figure 1 by dotted lines. The detri-

mental effect of the capacity C_i may be eliminated, and this capacity utilized to advantage by employing it in the type of circuit shown in Figure 2 for radio frequency amplification. The 5 latter incorporates such capacitive reactance in a filter construction interposed as a coupling between each pair of stages of amplification.

In Figure 2, I have shown an amplifier circuit which illustrates the principles of the present 10 invention, the circuit embodying the tubes 1, 2 preferably of the screen-grid type, the input circuit of the tube 1 being connected to the selector in the antenna circuit, as shown in Figure 1, and designated as "Signal Input" in Figure 2.

15 The plate circuit of tube 1 is connected through a grid condenser C_2 to the grid of the subsequent tube 2. A grid leak r_2 is connected from the filament to the grid of the tube 2, the output circuit of the tube 2 being coupled to any well known 20 type of utilization means. The input terminals of a filter member F are connected to the positive terminal of a source "B" and the plate circuit of tube 1.

If only a few filter sections are to be used, a 25 terminating resistance, well known in the art, may be used and is designated by R_t . The function of the terminating resistance is to cause the filter F to act approximately as if it was constructed of an indefinite number of sections as 30 far as its input impedance is concerned.

It will be observed that the filter member F is so arranged relative to the tube 1 that the tube 35 capacities C_i are connected across the input terminals of the filter member, and the filter member is so constructed that it has an impedance which acts as a pure and fairly constant resistance over a predetermined range of frequencies. The invention includes, then, employing the tube capacities of each stage of 40 amplification as the capacity (or portion of the capacity) required across the filter input terminals.

In Figure 3, I have shown an amplifier circuit, similar to that shown in Figure 2, in which the 45 filter member F comprises a low pass filter having two meshes or sections, the first capacity consisting of tube capacities C_i effectively in shunt with the plate-filament circuit of tube 1, and including, of course, the grid-filament 50 capacity of the subsequent tube 2. The inductances L_1 , L_2 , and capacities C_3 , C_4 are so chosen as to make the input impedance of the filter as high and uniform as possible over the range of frequencies to be amplified.

55 The voltage built up on the plate of the tube 1 is transferred to the grid of the subsequent tube 2 by a grid capacity C_2 , and the grid of tube 2 is maintained at a negative bias through a grid leak r_2 , as shown in Figure 1. The terminal resistance R_t is shown, as in Figure 2, connected to the filter sections as explained heretofore.

In Figure 4, there is shown a stage of amplification coupled to a subsequent stage (not shown) by the filter member of the type shown 65 in Figure 3, but simplified in that only one mesh or section is employed, the coupling being analogous in structure and operation to that shown in Figure 3 in every way.

70 A low pass filter is not the only coupling construction that can be employed between each pair of amplification stages. Figure 5 shows a band pass filter utilized as a coupling between the tube 1, and the subsequent stage of amplification (not shown), it being observed that the tube

capacities C_i are shunted across the input terminals of the filter, the filter including a pair of anti-resonant circuits I, II, in parallel, the latter circuits being coupled by a condenser C_5 .

It will be noted that the terminating resistance R_t is connected across the output terminal of the filter member, as explained heretofore. It is to be understood that the only requirements for constructing the filter member coupling are that it should call for a shunt capacity across its input terminals, the shunt capacity being the effective inter-electrode capacities of the coupled tubes, and that the filter member have a suitably high, and preferably uniform, impedance throughout the desired frequency range. It will be obvious that the utilization of a band pass filter coupling between each pair of stages involves the further advantage of discrimination against frequencies lying outside the desired band.

80 In Figures 6 I have shown an amplifier circuit, analogous to that shown in Figures 1, 2, 3 and 5 in which the grid of the subsequent tube 2 is coupled to the terminating impedance R_t , the latter then functioning simultaneously as a terminating resistance and a grid leak. In such a case, the grid-filament capacity is not effectively in shunt to the filter input, but to its output terminals.

85 It is to be observed that one of the input terminals of the filter coupling F is connected to the positive terminal of the source "B" and that one of the output terminals of the filter is also connected to the positive terminal of the latter source, or the filament source. In this latter type of circuit, it is to be understood that the filter F may be a high, low, or band pass type of filter member.

90 I have illustrated each stage of amplification as being of the screen-grid type of tube, but it is to be understood that if this type of tube is not used, resistance coupling increases the apparent grid-filament capacity of the tubes in accordance with well known formulæ. In that case the filters must be designed to operate with this apparent value of terminal capacity rather than the simple tube capacity alone.

95 While I have indicated and described only a few systems for carrying my invention into effect, it will be apparent to one skilled in the art that my invention is by no means limited to the particular organizations shown and described, but that many modifications in the circuit arrangements, as well as in the apparatus employed, may be used without departing from the scope of my invention as set forth in the appended claims.

100 What I claim is:

1. A radio frequency amplifier comprising a 105 pair of electron discharge tubes, means for impressing radio frequency currents upon the input circuit of one of the tubes, a condensive path of low impedance to such currents directly connecting the anode of said last tube to the control electrode of the other tube, a source of potential for the said anode, a filter having a proper terminating resistor and presenting a 110 substantially constant pure resistance as its impedance over a considerable range of radio frequencies, connected between said source and said anode, alternating current potential differences produced across said filter throughout said range being impressed upon said low impedance path.

115 2. A radio frequency amplifier comprising a 110

- pair of electron discharge tubes, means for impressing radio frequency currents upon the input circuit of one of the tubes, a condenser of low impedance to such currents directly connecting 5 the anode of said last tube to the control electrode of the other tube, a source of potential for the said anode, a filter having a proper terminating resistor, and presenting a substantially constant pure resistance as its impedance over a de- 10 sired range of radio frequencies, connected between said source and said anode, alternating current potential differences produced across said filter through said range being impressed upon said condenser, said filter including as an ele- 15 ment thereof the inter-electrode capacities of both tubes. 3. A radio frequency amplifier comprising a pair of electron discharge tubes, means for impressing radio frequency currents upon the input circuit of one of the tubes, a condenser directly connecting the anode of said last tube to the control electrode of the other tube, a source of potential for the said anode, a properly terminat- 20 ed filter path, presenting as its impedance over a desired range of radio frequencies a substantially constant pure resistance, connected between said source and said anode, alternating current potential differences produced across said filter path throughout said range being impressed upon 25 said condenser. 4. A radio frequency amplifier comprising a pair of electron discharge tubes, means for impressing radio frequency currents upon the input circuit of one of the tubes, a condensive path 30 of low impedance to such currents directly connecting the anode of said last tube to the control electrode of the other tube, a source of potential for the said anode, a low pass filter path having 35 a proper terminating resistance, and presenting as its impedance over a desired range of radio frequencies to be amplified, connected between said source and said anode, alternating current potential differences produced across said low pass filter path throughout said range being impressed upon said low impedance path. 5. A radio frequency amplifier comprising a pair of electron discharge tubes, means for impressing radio frequency currents upon the input circuit of one of the tubes, a condensive path of low impedance to such currents directly connecting the anode of said last tube to the control electrode of the other tube, a source of potential for the said anode, a band pass filter path including a proper terminating resistor, and presenting a substantially constant pure resistance as its impedance over a desired band of radio frequencies to be amplified, connected between said source and said anode, alternating current potential differences produced across said band pass filter path throughout said band being impressed upon said low impedance path. 6. A radio frequency amplifier including a pair of tubes, coupling means between the pair of tubes comprising a filter member including as an element thereof an effective capacity composed of the tube capacities of the tube preceding it, a proper terminating resistor connected across the filter output, the coupling means presenting a substantially constant pure resistance as its impedance over the amplifier operating range of frequencies, a source of potential for the anode of the preceding tube, said filter being connected between the anode and said source. 40 45 50 55 60 65 70 75 80 85 90 95 100 105 110 115 120 125 130 135 140 145 150
